United States Patent Office.

CYRUS W. SALADEE, OF NEWARK, OHIO, AND JOHN S. HALL, OF PITTSBURG, PENNSYLVANIA.

Letters Patent No. 78,612, dated June 2, 1868.

IMPROVED GRATER AND SLICER.

The Schedule referred to in these Letters Patent and making part of the same.

TO ALL WHOM IT MAY CONCERN:

Be it known that we, CYRUS W. SALADEE, of Newark, county of Licking, State of Ohio, and JOHN S. HALL, of Pittsburgh, Pennsylvania, have invented a new and improved Mode of Constructing Graters and Slicers for grating or slicing fruits, &c.; and we do hereby declare that the following is a full and exact description thereof, reference being had to the accompanying drawings, and to the letters of reference marked thereon.

Our invention consists in a cheap and simple machine for grating or slicing fruits and vegetables, the grater or slicer being made to reciprocate (by turning a bell-crank) under the receptacle in which the fruit or vegetable is placed. In the drawings—

Figure 1 is an end elevation.

Figure 2 is a side elevation.

Figure 3 is a view showing the "slicer."

A is a suitable frame, bent like a reversed U, and provided with a thumb-screw, so as to be fastened to the table when used.

B is a sliding table formed of cast metal, and sliding in grooves, a, in the frame A. From the centre of this table a fork, C, projects downward.

D is the operating bell-crank, pivoted in the frame A, the straight part d of the yoke playing in the fork C, so that, as the crank revolves, it imparts a reciprocating movement to the table B.

E is the holder at the top of the frame, and in which the fruit to be grated or sliced is put. e is a hollow plug, to be put in the holder when a smaller fruit or vegetable is to be grated or cut.

G is the grater, made as usual, and fixed to the upper surface of the sliding table.

When the instrument is to be used as a "slicer," the "slicer" S, consisting of a plate, S, and knife, S', is to be fixed to the table, and the grater G removed.

In using our "grater," the radish or fruit is placed in the holder E and pressed downward while the crank is turned. In this manner our machine grates and slices well and rapidly.

Having thus fully described our invention, what we claim as new, and desire to secure by Letters Patent, is—

1. The frame A, table B, and crank D, substantially as described, in combination with the grater G, substantially as and for the purposes set forth.

2. The frame A, table B, and crank D, substantially as described, in combination with the slicer S, substantially as and for the purposes set forth.

3. The hollow plug e, in combination with the holder E, in the manner and for the purpose substantially as shown and described.

In testimony that we claim the above, we hereunto subscribe our names.

CYRUS W. SALADEE,
JOHN S. HALL.
